UNITED STATES PATENT OFFICE.

HENRY FINK, OF NEWARK, NEW JERSEY.

DESIGN FOR A STAND FOR HOLDING CIGARS, PIPES, MATCHES, AND LIGHTERS.

46,165.

Specification for Design.

Patented July 28, 1914.

Application filed May 22, 1914. Serial No. 840,385. Term of patent 14 years.

To all whom it may concern:

Be it known that I, HENRY FINK, a citizen of the United States, residing at Newark, county of Essex, and State of New Jersey, have invented a new, original, and ornamental Design for Stands for Holding Cigars, Pipes, Matches, and Lighters, of which the following is a specification, reference being had to the accompanying drawing, forming part thereof.

Figure 1 is a top view of my new stand for holding cigars, pipes, matches and lighters, and Fig. 2 is a side view thereof.

I claim:

The ornamental design for a stand for holding cigars, pipes, matches and lighters, as shown.

HENRY FINK.

Witnesses:

M. A. JOHNSON,
H. TRAUTVETTER.
